Primary Examiner — Mitchell I. Siegel(74) *Attorney, Agent, or Firm* — Kolisch Hartwell, P.C.(57) **CLAIM**

We claim the ornamental design for a fishing rod carrier, as shown.

DESCRIPTION

FIG. 1 is a front, top, and left view of a fishing rod carrier showing the new design;

FIG. 2 is a rear, bottom, and right view thereof;

FIG. 3 is a rear elevation view thereof;

FIG. 4 is a front elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines shown are included for the purpose of illustrating unclaimed subject matter and forms no part of the claimed design.

1 Claim, 4 Drawing Sheets(56)
